UNITED STATES PATENT OFFICE.

CHARLES A. SWEET, OF BOSTON, MASSACHUSETTS.

DESIGN FOR A TOMBSTONE.

SPECIFICATION forming part of Design No. 33,812, dated December 25, 1900.

Application filed December 1, 1900. Serial No. 38,374. Term of patent 7 years.

To all whom it may concern:

Be it known that I, CHARLES A. SWEET, a citizen of the United States, residing at East Boston, in the county of Suffolk and State of Massachusetts, have invented and produced a new and original Design for Tombstones, of which the following is a specification, reference being had to the accompanying drawings, forming part thereof, in which—

Figure 1 is a front elevation of a tombstone embodying my design, and Fig. 2 a side elevation of the same.

As shown in the drawings, the leading or material features of my design consist of a substantially rectangular base A, on the top of which a pedestal B is arranged, said pedestal having its faces converging toward its upper end, as illustrated, each face being ornamented by horizontally-arranged straight and curved surfaces. Mounted upon the pedestal is a cross the upright C of which is formed at its upper end with a curved portion D and with the laterally-extending curved portions E disposed on opposite sides

of said curved portion D and at the lower end 25 thereof. The cross-piece F is formed at its respective ends with curved portions D' and E', arranged the same as curved portions D and E of the upright. The upright C is provided on its front and rear faces, at the juncture of the cross-piece F therewith, with raised oval-shaped portions G, having raised ornamental borders H. Said upright C is also formed on its respective sides and at a point intermediately of the pedestal and cross-piece 35 with raised or bulged portions I, tapering from their centers into the side surfaces of the upright.

Having thus fully described my invention, what I claim as new, and desire to secure by 40 Letters Patent of the United States, is—

The design for a tombstone, as herein shown and described.

CHARLES A. SWEET.
